(57) **CLAIM**

The ornamental design for an all-terrain vehicle as shown and described.

DESCRIPTION

FIG. 1 is a front view of an all-terrain vehicle showing my new design;

FIG. 2 is a rear view thereof;

FIG. 3 is a left side view thereof;

FIG. 4 is a right side view thereof;

FIG. 5 is a top plan view thereof;

FIG. 6 is a bottom plan view thereof;

FIG. 7 is a front and left side perspective view thereof; and, FIG. 8 is a rear and right side perspective view thereof.

The light grayed-out portions showing of the all-terrain vehicle are provided for the purpose of illustrating environmental structure and do not form part of the claimed design.

1 Claim, 8 Drawing Sheets
